UNITED STATES PATENT OFFICE.

CLARENCE A. SCHWANKE, OF WILLOW CITY, NORTH DAKOTA.

OPERATING MECHANISM FOR WASHING-MACHINES.

1,253,634.

Specification of Letters Patent. Patented Jan. 15, 1918.

Application filed December 8, 1915. Serial No. 65,724.

To all whom it may concern:

Be it known that I, CLARENCE A. SCHWANKE, a citizen of the United States, residing at Willow City, in the county of Bottineau and State of North Dakota, have invented certain new and useful Improvements in Operating Mechanism for Washing-Machines, of which the following is a specification.

- 10 My present invention has relation to certain new and useful improvements in washing machines and more essentially, to an improved operating mechanism therefor; and as its primary object, it contemplates 65
15 the provision of a novel apparatus of the above nature which is constructed so as to be efficient in operation and wherein the parts are so arranged whereby they are not likely to get out of order.
20 A further object of my invention is to provide a device of the type in question that is extremely simple in construction, strong and durable, and highly practical from both the standpoint of the manufacturer and the standpoint of the user; and which, it is believed, may be manufactured 75
25 at a comparatively low cost.

Various other objects and advantages will become apparent during the continuance of 30 the following description.

In the accompanying drawings wherein like characters designate like parts throughout the several views;

Figure 1 is a view in side elevation illustrating my invention as in its preferred embodiment, the several parts being shown in operative relation;

Fig. 2 is a view in top plan showing more clearly the relative disposition of the wringer 40 actuating mechanism;

Fig. 3 is a view similar to Fig. 1 showing parts of the supporting stand and the clothes container broken away to illustrate the construction thereof more clearly;

45 Fig. 4 is a view in detail of a novel form of rubber that is employed;

Fig. 5 is a view showing the supporting stand broken away and in section to disclose more clearly the mechanism for oscillating the container shaft;

50 Fig. 6 is a view of the container showing the same broken away and in section and illustrating the means for drawing the water or other liquid therefrom;

Fig. 7 is a fragmentary view of the supporting stand showing the mechanism for actuating the container shaft;

Fig. 8 is a detail view of the improved belt shifting mechanism that is also employed;

Fig. 9 is a cross sectional view taken on the line 9—9 of Fig. 3.

In reducing my invention to practice, I first provide a suitable supporting stand, which in the present embodiment consists of a series of legs 10 connected through the medium of end and side pieces 11 and 12 respectively, and having a platform 13 associated therewith, such as shown in Fig. 3. In order to further insure the rigidity of the legs 10, at all times, they may be also connected intermediate their ends, through the medium of side and end brace rods 14 and 15 respectively. Although this type of supporting structure may be advantageously employed, it is to be fully understood that I do not limit myself to the specific construction in any way in view of the fact that my invention may be also employed in connection with various other forms of supporting structures.

With a view of supporting the clothes container 16, I equip the same with a carrying shaft 17 that is arranged to extend through an opening 18 in the platform 13 (see Fig. 3) and engage with a guide member 19 that is carried by the bracing rods 14. Upon its under face the container 16 carries a bearing block 20 which may be secured thereto as at 21 and which is designed to coöperate with a similarly formed bearing block 22 that is carried upon the platform 13 as at 23. Suitable anti-friction bearings 24 may be interposed between the bearing blocks 20 and 22 respectively so as to efficiently support the container in movable relation with the supporting structure. In order to preclude accidental dislodgment of the carrying shaft 17, during the operation of the device, the same may be provided with a collar 25 which is adjustably mounted through the medium of a fastening member 26, to coöperate with the guiding member 19, in the manner shown. Although not essential to the efficient operation of the device, it is pointed out that the upper end of the carrying shaft may be squared as at 27 for reception into a similar opening in

the carrying block 20, whereby the connection with the bearing block and the retainment of the latter in a rigid position at all times is assured. Furthermore, this method 5 of associating the carrying shaft with the bearing block eliminates the necessary of journaling the upper end thereof into the bottom of the clothes container such as would not only decrease the cost of manufacture of the device, but in all probability 10 derogate from the efficiency of the container itself.

Referring to Fig. 3, it will be noted that the bearing block 22 is provided with a suitable opening 28 that is coaxially alined with the opening 18 of the platform so as to receive the carrying shaft 17 and permit free operation thereof at all times.

While I do not limit myself to that type 20 of container shown, it is pointed out that this form may be used to advantage in connection with the associated mechanism. In its present embodiment, the container consists of a bottom member 29 which may be 25 constructed of any desirable material, that is connected in a suitable manner with the side wall or casing structure 30. As is clearly apparent upon reference to Fig. 3, bolts such as designated by the numeral 21 30 may be passed through the bottom member 29 for facilitating the attachment of the bearing block 20 thereto; however, as above pointed out, the necessity of journaling the carrying shaft 17 in the bottom member has 35 been eliminated. The inner face of the bottom member 29 and the casing structure 30 is provided with any suitable means to exert rubbing action on the clothes or other articles being acted upon, during operation and 40 to this end I have shown the same provided with spaced slats 31 which may be affixed thereto in any desired manner. Adjacent its upper end the casing structure 30 of the container is provided with a projecting ledge 32 which is designed to support, at 45 certain times, a cover member 33; consequently, any suitable means may be employed to lock the cover 33 in place.

A rubber, such as shown in detail in Fig. 4, is designed to operate within the container 16 in a manner whereby the thorough cleaning of the clothes is insured. This rubber, in its present embodiment, is shown in the form of a circular body structure 34 5 having spaced openings 35 to permit the passage of the fluid therethrough and a series of spaced rubbing ribs 36 to engage with the clothes in the usual manner. A reinforcing disk 37 is fixed to the rubber, such as shown at 38 which is designed to connect with one end of a suitably formed carrying stud 39; the latter being journaled through an opening 40 formed in the cover 33 in the manner shown. I also provide suitable means to guide the stud 39 during

movement of the rubber and to retain the same in a stationary position with respect to the container 16, which means will be subsequently described.

In order to facilitate the discharge of the 70 liquid contents of the container 16 and at the same time facilitate the interchanging of the water during the washing of the clothes, I provide the container with a suitable faucet 41 that is arranged in the manner whereby its receiving pipe 42 communicates with the container at a point sufficiently low or in alinement with the inner face of the bottom member 29. In accomplishing this, it may be necessary to cut 80 away the member 29 such as indicated by the numeral 43 whereby the entire liquid contents of the container may be dispensed without tilting the same or moving it in any manner.

With a view of providing mechanism to properly actuate the container 16 and other devices that may be associated therewith, I employ a stub shaft 44 that is journaled through a bracket 45 on one of the brace 90 rods 14 and another bracket 46 mounted on a transversely arranged supporting member 47. A driving pulley 48 is suitably keyed to the stub shaft 44 as at 49 (see Fig. 7), while a second pulley 50 is mounted to be 95 movable thereon and provided with a worm gear 51. Although not limiting myself to any specific form of connection between the loose pulley 50 and the worm gear 51 thereof, it is pointed out that the said gear may 100 be cast integral with the pulley, if such is desired. This would undoubtedly decrease the cost of manufacture of the elements and at the same time insure a more efficient connection therebetween. In the present embodiment, one terminal of the worm gear 51 is arranged so that longitudinal movement in one direction with respect to the stub shaft 44 is limited by the fixed pulley 48, while the other terminal is normally 110 arranged in close proximity to the bearing 45 whereby movement in an opposite direction will also be prevented. This will insure efficient connection between the worm gear mechanism and the apparatus associated therewith to the end that the device, as a whole will operate efficiently at all times.

Intermediate its ends, the supporting member 47 is provided with an upstanding stud 52 upon which is rotatably mounted a beveled gear 53 of relatively large diameter which meshes with a like gear of smaller diameter designated by the numeral 54, that is carried on the stub shaft 44. In order to eliminate friction between the gear wheel 53 and the supporting member 47, it may be necessary to interpose a spacing member such for instance as designated by the numeral 55 therebetween; although it will be understood that this is not essential. Likewise, it may 125 130

be necessary to arrange a spacing member such as shown at 56 between the beveled gear 54 and the bearing 46 of the stub shaft such as illustrated in Fig. 1 of the drawings.

5 The carrying shaft 17 is in turn provided, adjacent its lower ends, with a crank arm 57 which is adjustably connected therewith through the medium of a fastening member 58 and provided at one end with an upstanding stud 59 such as shown in Fig. 3. To impart movement from the stub shaft 44 to the carrying shaft 17, I further provide a link 60 which has its respective ends loosely connected with the stud 59 of the crank arm 57, 15 in one instance and to a stud 61 that is carried on the gear wheel 53, in the other instance. Consequently, it will be recognized that the tendency of the gear wheel 53 will be to impart movement to the carrying shaft 20 17 through the medium of said link.

The carrying shaft 17 is further provided with oppositely projecting arms 62 whose free ends are connected with heavy duty retractile springs 63 and 64 respectively, that 25 are in turn connected to the supporting structure of the device, by screw eyes or bolts as shown at 65 and 66 respectively in Fig. 3. These retractile springs are designed to normally retain the carrying shaft 17 in a position 30 whereby it will be resiliently held against rotative movement. Upon movement of the gear wheel 53, however, the carrying shaft 17 will be actuated so as to cause movement of the arms 62 against the 35 tension of the respective springs 63 and 64 in an obvious manner. The rotation of the gear wheel 53 does not, therefore, effect the entire rotation of the carrying shaft 17 since as soon as the connecting link 60 passes a dead 40 center the retractile springs acting on the shaft by way of the arms 62 effects the operation thereof oppositely to its initial movement, therefore, the continued agitation of the contents of container caused by the oscillation 45 of the carrying shaft will insure the thorough cleaning of the material acted upon.

I also provide the supporting structure with a suitable stand such as designated in 50 its entirety by the numeral 67 (see Fig. 1) which, in the present embodiment, consists of standards 68 and 69 respectively, that are suitably connected with the supporting structure and which in turn carry a transverse supporting beam 70 that may be attached thereto through the medium of stay bolts 71. This stand may be constructed of any desirable material, such for instance as metal or wood and is primarily adapted to 55 support a clothes wringer (not shown) and novel operating mechanism therefor. In order that the wringer may be more efficiently operated in connection with the stand of this particular construction, the latter may 60 be provided with suitable spacing boards 72

whereby the clothes being rubbed will be kept out of engagement with the container structure at all times.

In conjunction with the stand 67, I further employ a suitable supporting bracket 70 such as designated by the numeral 73 which being substantially U-shaped when viewed in side elevation, may be secured to the stand 67 as at 74. This supporting frame is preferably constructed of metal whereby it may be capable of withstanding the pressure subjected theron, at certain times, and thus insure the efficient operation of the device, at all times. It may be in turn provided with a suitable cover member 75 so as to 80 completely protect the interior mechanism thereof from moisture, rust, dirt and other foreign material. While I do not desire to limit myself to any specific means for affixing the cover member in place, it is pointed 85 out that set screws 76 such as shown in Fig. 3 may be used in this capacity. Therefore, it will be seen that the cover may be quickly and easily removed or placed in position such as will expedite oiling or the adjustment of 90 the mechanism carried by the frame 73.

Adjacent its upper end, the cover member 73 is slightly enlarged as indicated by the numeral 77, the said enlargement being in turn provided with a through opening or slot 78 and a series of rack teeth 79 adjacent the aforesaid slot. The function of the enlargement 77 and the various parts thereof will be subsequently pointed out.

I also find it expedient to provide another 100 shaft 80 which has its upper end journaled through the lower wall of the frame 73 while it is supported adjacent its other end through the instrumentality of a bearing member 81. At its lower end the shaft 80 105 carries a pinion 82 for meshing engagement with the worm gear 51 above referred to, while a beveled gear 83 is keyed to the upper end thereof, as shown in Fig. 1 to mesh at certain times with other beveled pinions 84 110 and 85 respectively that are carried upon a slidable sleeve 86. The shaft 86, in the present embodiment, is reduced slightly at points indicated by the numerals 87 and 88 for slidable engagement with the respective 115 side walls of the frame 73 while one end portion is squared as at 89 for engagement with the wringer mechanism (not shown). In order to properly shift the sleeve 86 so that a selected one of the gears 84 and 85 may be 120 brought into meshing engagement with the gear wheel 83, I provide the same with a bearing 90 to which may be pivotally connected at 91, an operating lever 92, the latter being arranged to project through the slot 125 78 of the cover member 75 (see Fig. 1) and pivotally connected to the enlarged portion 77 thereof as at 93. The operating lever is in turn provided with a holding pawl 94 that may be brought into or out of engage- 130

ment with the rack teeth 79 through the instrumentality of a pivoted actuating member 95 whereby the operating lever may be held in certain adjusted positions, as is obvious. By properly shifting the sleeve 86, the selected one of the gears 84 and 85 may be brought into engagement with the gear wheel 83 and thus the direction of rotation of the shaft 86 reversed. This renders the mechanism very applicable to conventional forms of wringing devices, since the direction of the rotation of the wringer rolls may be properly controlled and the direction of rotation reversed when the clogging of the material therebetween occurs.

A belt 96 from a suitable source of power is arranged to operate in conjunction with the pulleys 48 and 50 respectively whereby the washing machine or the wringer mechanism may be actuated. Thus in order to facilitate the shifting of the belt from one pulley to another I provide the supporting structure of the device with a projecting supporting arm 97 which is slightly enlarged adjacent one end as at 98 and pivotally supports an actuating lever 99 as at 100. The enlarged portion 98 of the supporting arm may be provided at a suitable point with a series of notches 101 for cooperation with a pawl 102 that is in turn carried by the operating lever through the medium of a slidable rod or other carrying member 103. A pivoted member 104 may be employed to properly actuate the rod 103 and the lug carried thereby while spaced bearings 105 may also be provided to guide the rod 103 and insure the proper seating of the pawl 102. The supporting structure of the device is further provided with a carrying plate 106 through an opening 107 of which is journaled a carrying rod 108. One end of this carrying rod is pivotally connected as at 109 to the operating lever 99, while it carries a pair of spaced engaging fingers 110 at a point intermediate its ends to be associated with the belt 96, in the manner clearly shown in Fig. 2. Set screws as designated by the numeral 111 may also be employed for the purpose of retaining the respective engaging fingers 110 in certain adjusted positions upon the shaft or rod 108 whereby they may be advantageously employed in connection with belts of varying widths. Consequently, it will be seen that by rocking the lever 99, the rod 108 will be thrust inwardly or outwardly with respect to the supporting structure, such as the case may be, whereby the belt 96 may be moved from one pulley to another. When on the pulley 48 it will serve to operate the container 16 in the manner hereinbefore described while when on the pulley 50, the wringer actuating mechanism will be operated. However, by properly manipulating

the belt 96 it may be made to engage with both of the pulleys at one time so that the container and the wringer operating mechanism may be actuated simultaneously. I desire to lay great stress on this particular feature of the device, since it is believed that it adds materially to the utility thereof.

As hereinbefore stated, I also provide means for retaining the rubbing member 34 against rotation, with respect to the container 16 but to permit slight vertical movement thereof to be caused by the action of the contents of the container. Therefore, to this end I provide the stand 67 with a suitable supporting block 112 to which is movably connected one end of a carrying arm 80 113. The other end of the carrying arm is provided with a squared opening such as designated by the numeral 114 for reception of the squared supporting stud 39 that carries the rubbing member. Consequently, it will be noted that while the rubbing member is free to move both laterally and vertically with respect to the container, its rotative movement will be effectually prevented. By reason of this construction, the rubbing member will automatically adjust itself in accordance with the amount of material in the container, whereby it will be efficient in operation at all times.

The operation of my invention is substantially as follows:—

As hereinbefore stated, the belt 96 imparts movement to the respective pulley, such for instance as the pulley 48 thereby causing operation of the shaft 44 and the consequent operation of the beveled gear 53 through the beveled pinion 54. Such movement of the beveled gear 53 will cause the actuation of the carrying shaft 17 such as before stated, whereby the contents of the container 16 will be kept in a continued state of agitation so as to bring the clothes in engagement with the side and bottom walls thereof and the under corrugated or ribbed face of the rubbing member 34. By this arrangement, it is believed that the clothes or other material being washed will be thoroughly cleaned.

On the other hand, when the belt 96 engages with the pulley 50, the worm gear 51 will be actuated so as to cause rotation of the pinion 82 and the respective shafts 80 and the consequent rotation of the beveled gear wheel 83. The operator now adjusts the hand lever 92 so as to bring a selected one of the gears 84 or 85 in engagement with the said rotating gear wheel 83 whereby the wringer mechanism (not shown) will be actuated and the rolls thereof rotated in a desired direction. Furthermore, it will be seen that by properly shifting the belt 96 it may be brought to engage with both of the pulleys at the same time, thus causing the

simultaneous actuation of both the container 16 and the respective wringer actuating mechanism.

From the foregoing it is believed that the 5 advantages and novel features of my invention will be readily understood and, therefore, further detail description is deemed unnecessary.

In reducing my invention to practice I 10 find that the form referred to herein as the most practical and preferred embodiment is the most efficient, but realizing that certain conditions will necessarily vary in concurrence with the adoption of my device, I desire to emphasize the fact that various minor 15 changes in the details of construction and in the proportion of parts may be resorted to when required without sacrificing any of the advantages of my invention as defined in 20 the appended claim.

Having thus fully described my invention, what I claim as new and desire to secure by Letters Patent is:—

The combination with an oscillatory element, of an operating mechanism therefor 25 including a stub shaft, a pulley keyed to

said shaft, a supporting frame, a wringer carrying shaft, a second shaft, a gear wheel on said second shaft, pinions on said wringer carrying shaft, means to shift said pinions into and out of engagement with said gear wheel whereby said wringer carrying shaft will be rotated in two directions, means to retain said pinions in adjusted positions, a pulley loosely mounted on said stub shaft, 30 a belt for driving both said pulleys, worm gear mechanism connected with said last mentioned pulley, a pinion keyed to said second shaft and meshing with said worm gear mechanism, a supporting arm, an operating lever pivotally mounted on said supporting arm, means to retain said lever in adjusted position, and means carried by said operating lever to shift said belt in a position whereby said pulleys will be operated 35 simultaneously.

In testimony whereof I affix my signature in presence of two witnesses.

CLARENCE A. SCHWANKE.
